Attorneys.

UNITED STATES PATENT OFFICE.

PAUL TRANGOTT JULIUS ESTLER, OF LONDON, ENGLAND.

TROLLEY COLLECTOR.

Application filed May 2, 1922. Serial No. 557,914.

To all whom it may concern:

Be it known that I, PAUL TRANGOTT JULIUS ESTLER, a subject of the King of Great Britain, and resident of London, England, have invented certain new and useful Improvements in Trolley Collectors, of which the following is a specification.

This invention relates to trolley collectors for electrically driven tramcars or road motor vehicles and more particularly to that type of trolley collector which comprises two or more trolley poles mounted one above the other on the same vertical axis.

The object of the present invention is to so construct and arrange the various parts that the body of the trolley collector is insulated from any electrical contact whatsoever and in order that my invention may be clearly understood and readily carried into effect I have illustrated a constructional form of the same in the accompanying drawing wherein similar reference characters relate to similar parts in both figures—

Figure 1 being an elevation and partial section and

Figure 2 a section on line 2—2 in Fig. 1. Referring to the said drawing the base plate *a* of the trolley collector body which is mounted in the usual manner on the top of the vehicle is shewn with the hollow trunnion *b* on which are rotatably mounted the cap *c* and sleeve *d* carrying the upper and lower trolley poles *e* and *f* respectively, a second sleeve *g* provided with the horizontal flange *h* being also mounted on the trunnion *b* and fixed thereto between the cap *c* and sleeve *d*. *i* represents a contact member carried by the insulator *j* secured to the underside of the top of the rotatable cap *c* and adapted to rotate on and thereby make contact with a fixed contact member *k* carried by the flanged rings *l* and *m* which are supported on the insulator *n* mounted on the internal circular flange *o* of the trunnion *b*. *p* represents another movable contact member carried by the bracket *q* attached to the rotatable sleeve *d* but insulated therefrom at *r*, the contact member *p* being adapted to slide on and thereby make contact with the ring *s* carried by the flanged ring *t* secured to the fixed sleeve *g* and supporting the fixed contact member *u*; insulators *v*, three of which are shewn in the drawing, being disposed between the flange *h* of the sleeve *g* and the horizontal flange of the

ring *t* for the purpose of suspending the ring *t* from the flange *h*.

By this construction the metal body of the trolley collector is preserved from any electrical contact whatsoever, the insulated cables *w*, *x* conveying the current from and to the poleheads *y* and *z* respectively which are mounted on the poles *e* and *f* but insulated therefrom as shewn at *z'*.

Polehead *y* receives current from the overhead conductor *1* from whence it passes through cable *w* and the rotatable contact member *i* to fixed contact member *k* and from thence by wire *w'* to the motor on the vehicle from which it is returned by the cable *x'* to the fixed contact member *u* and from thence by the rings *t* and *s* and the sliding contact member *p* to the return cable *x*, polehead *z* and overhead conductor wire *1*.

The ability of the poles *e* and *f* to accommodate themselves independently to the side to side movements of the vehicles on the road and the irregularity of spacing of the overhead conductor wires is not impaired in any way.

Under certain conditions both in electric tramways and in road motor vehicles (for example where a three wire system is used) it is expedient to use more than two collector trolley poles, even then my invention is applicable, for any reasonable number thus mounted can be insulated in the manner described.

What I claim is:—

1. In combination, a trolley collector body, a cap and a sleeve both rotatably mounted on said body and a second sleeve fixed to said body an upper trolley pole carried by said rotatable cap and a lower trolley pole carried by said rotatable sleeve both said trolley poles having pole heads electrically insulated from said poles for contact with overhead electric conductors, electric conductors leading from and to said pole heads, movable contact members carried by said rotatable cap and said rotatable sleeve, fixed contact members carried by the trolley collector body, and electric insulating means mounted on said rotatable cap and trolley collector body, and also on said rotatable and fixed sleeves.

2. In combination a trolley collector body with a hollow trunnion projecting therefrom, a cap and a sleeve both rotatably mounted on said trunnion and a second sleeve fixed to

said trunnion, an upper trolley pole carried by said rotatable cap and a lower trolley pole carried by said rotatable sleeve, both said trolley poles having pole heads electrically insulated from said poles for contact with overhead electric conductors, electric conductors leading from and to said pole heads, a movable contact member carried by an insulator attached to said rotatable cap, 10 a fixed contact member supported on another

insulator mounted on the aforesaid trunnion, a second movable contact member carried by said movable sleeve and insulated therefrom, a second fixed contact member supported on a flanged ring secured to the aforesaid fixed sleeve and insulating members between said flanged ring and said fixed sleeve.

In testimony whereof I affix my signature.
PAUL TRANGOTT JULIUS ESTLER.
